United States Patent

Des. 240,404
Patented July 6, 1976

240,404

MODULAR SHIPPING CONTAINER

Frederic J. Singer, 715 S. Nakama Drive,
Santa Ana, Calif. 92704

Filed Jan. 20, 1975, Ser. No. 542,203

Term of patent 14 years

Int. Cl. D9—04

U.S. Cl. D9—246

FIG. 1.

FIG. 2.

FIG. 3.

FIG. 4.

FIG. 5.

FIG. 1 is a front elevational view of a modular shipping container, showing my new design;

FIG. 2 is a side elevational view, the opposite side being substantially a mirror image thereof;

FIG. 3 is a rear elevational view;

FIG. 4 is a top plan view; and

FIG. 5 is a bottom plan view thereof.

I claim:

The ornamental design for a modular shipping container, as shown and described.
